UNITED STATES PATENT OFFICE

155,999

DESIGN FOR A COMBINED WALL TYPE ASH TRAY AND HOLDER FOR MATCHES AND OTHER ARTICLES

Joseph Grzeca, Chicago, Ill.

Application August 7, 1947, Serial No. 140,754

Term of patent 3½ years

(Cl. D44—24)

To all whom it may concern:

Be it known that I, Joseph Grzeca, a citizen of the United States, residing at Chicago, Cook County, Illinois, have invented a new, original, and ornamental Design for a Combined Wall Type Ash Tray and Holder for Matches and Other Articles, of which the following is a specification, reference being had to the accompanying drawing, forming a part thereof, wherein,

Fig. 1 is a front elevational view of a combined wall type ash tray and holder for matches and other articles, showing my new design;

Fig. 2 is a side elevational view;

Fig. 3 is a rear elevational view;

Fig. 4 is a top plan view; and

Fig. 5 is a bottom plan view thereof.

I claim:

The ornamental design for a combined wall type ash tray and holder for matches and other articles, as shown.

JOSEPH GRZECΑ.
